ATTORNEYS.

UNITED STATES PATENT OFFICE.

FREDERICK C. CLEMENT, OF PHILADELPHIA, PENNSYLVANIA.

CLOSURE FOR RECEPTACLES.

Application filed April 1, 1925. Serial No. 19,789.

To all whom it may concern:

Be it known that I, FREDERICK C. CLEMENT, a citizen of the United States, residing at Philadelphia, in the county of Philadelphia and State of Pennsylvania, have invented certain new and useful Improvements in Closures for Receptacles, whereof the following is a specification, reference being had to the accompanying drawings.

This invention relates to closures for receptacles such as cans, jars, bottles, decanters, or similar vessels used more particularly for foods and beverages.

The present invention is directed to improvements in a closure of the type referred to whereby a yieldingly snug, substantially fluid and air tight fit is had with the receptacle without imposition of excessive restraint such as would render the removal of the closure difficult of accomplishment.

A further object is to secure the above desideratum in a closure capable of being sterilized, without detriment thereto, for maintenance in an absolutely sanitary condition.

Other objects and attendant advantages will be manifest from the detailed description which follows of a typical embodiment of this invention.

With reference to the drawings, Fig. I shows a beverage receptacle with a closure conveniently featuring my improvements.

Fig. II is a bottom plan view of the closure on a somewhat larger scale than that of Fig. I; and

Fig. III is an axial sectional view of the closure.

The receptacle chosen for convenience of illustration herein is in the form of a decanter comprising a flask 10 of glass that is vacuum-jacketed as at 11, and protected by an external casing 12 of metal in accordance with customary practice.

In adapting my invention for use in connection with a receptacle of this sort, I provide a stopper 13 which is constructed throughout from sheet metal. The upper portion or head 14 of this stopper 13 is appropriately fashioned to the form of a grasp knob 15 that has a circumferential basal flange 16 designed to serve as a cover or cap over the mouth of the receptacle as shown in Fig. I. The lower or depending portion 17 of the stopper is slightly tapered to facilitate its introduction into the mouth of the flask 10, and formed to spiral cross-

sectional configuration as set forth to best advantage in Fig. II, from a strip of flexible or springy sheet material. Radially-armed top and bottom spiders 18, 19 brace the spiral 17 from within, a substantial extent 20 at one end of the strip being however left free, as shown, for a purpose which will presently become apparent. The parts 14, 17 of the stopper are secured together by an axially-disposed headed screw 21 which is welded or soldered fast to the spiders 18, 19 and takes into a collar 22 concealed within the grasp knob 15. In addition, I preferably weld or solder the upper spider 18, and the top edge of the spiral 17 (with exception of the end 20) directly to the flat bottom surface of the head 14.

In applying the stopper to the receptacle, the free end 20 of the spiral 17 will yield to compression as the latter is introduced into the mouth of the flask 10, and will thereafter be maintained by virtue of its springiness, or in other words, its capacity for circumferential contraction, in close snug contact with the flask wall. Under this condition, and in view of the protection afforded by the flange 16 of the stopper 13, good, reliable air tightness is secured so that the original temperature of the receptacle contents is maintained for the maximum possible period. The stopper 13 is furthermore effectively held against easy displacement in the vent of accidental upsetting of the receptacle, and the contents thus insured against spilling in such a contingency. The open metallic construction of the stopper 13 renders its cleaning by sterilization very easy, and obviates the germ-breeding interstices or pits of cork or rubber closures such as ordinarily employed in connection with receptacles of the type herein specifically described.

The application of my invention to closures for containers of any of the other kinds whereto reference has been made in the introductory paragraph of the specification, will obviously be attended by advantages analogous to those just pointed out without requiring further detailed explanation.

Having thus described my invention, I claim:

1. A closure for receptacles comprising a grasp and a stopper portion, said stopper portion being of taper-spiral cross-section,

and means laterally bracing the spiral stopper portion to the grasp with the outer end of the former left free to permit circumferential contraction whereby the closure is 5 snugly fitted into the receptacle mouth.

2. A closure for receptacles comprising a grasp and a stopper portion, said stopper portion being of taper-spiral cross-section, and means laterally bracing the spiral portion in different planes to the grasp with the outer end of the former left free to permit circumferential contraction and expansion, whereby the closure may be snugly seated 10 into the receptacle mouth.

15 3. A closure for receptacles comprising a grasp and a stopper portion, said stopper portion being of taper-spiral cross-section, and spaced lateral spiders internally bracing the spiral stopper to the grasp with the outer end of said stopper left free to permit circumferential contraction, whereby the closure is 20 snugly fitted into the receptacle mouth.

4. A closure for receptacles comprising a grasp and a stopper portion, said stopper portion being of taper-spiral cross-section, and spaced lateral spiders having a connecting axial element rigidly bracing the spiral stopper to the grasp base with the outer end 25 of said spiral stopper left free to permit

circumferential expansion and contraction, for the purposes specified.

5. A closure of the type described comprising a hollow sheet metal grasp having a basal flange functional as the cover for a 35 receptacle and a strip metal stopper portion, said stopper portion being of taper-spiral cross-section, spaced spiders with a rigid axial connection laterally bracing the stopper to the grasp base, and a substantial portion of stopper outer end left free for the purposes specified.

6. A closure of the type described comprising a hollow sheet metal grasp having a substantially flat base functional as the 45 cover for a receptacle and a strip metal stopper portion, said stopper portion being of taper-spiral cross-section, upper and lower spaced spiders having a rigid axial connector laterally bracing the strip spiral to 50 the grasp base with a substantial portion of its outer end left free, said upper spider and the top of the spiral stopper—with the exception of the free outer end—being permanently united to the aforesaid grasp base. 55

In testimony whereof, I have hereunto signed my name at Philadelphia, Pennsylvania, this 27th day of March, 1925.

FREDERICK C. CLEMENT.
